UNITED STATES PATENT OFFICE.

THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A COR-
PORATION OF MICHIGAN.

CONTINUOUS TRAIN-CONTROL SYSTEM.

Application filed December 12, 1925. Serial No. 74,983.

This invention relates to the control of railway trains by means of high frequency currents propagated in the rails of tracks which are divided into blocks, a current propagating device being connected to the rails of each block, preferably at the exit end thereof, and each propagating installation embodying means influenced by the current in the rails of the block to which it is connected, and its object is to provide means whereby vacuum tubes may be utilized to provide train control currents of different wave lengths to control the operation of the trains passing over the track sections to which said tubes are connected, the wave lengths being determined by the occupancy of the track in advance.

A further object of this invention is to provide an electro-pneumatic valve to control the operation of the train breaks and signal lamps, circuits and a current source connected thereby to said valve and lamps, relays to control the operation of said valve and lamps, and vacuum bulbs and collector circuits and instrumentalities connected thereto for picking up the currents propagated in the rails and utilizing them for selecting the circuit to the lamp intended to designate the condition of the rails over which the train is passing.

In the accompanying drawings, Figs. 1, 2, 3 and 4 are diagrams of circuits and instrumentalities positioned along the track and mounted on locomotives embodying the present invention, the direction of travel being from right to left and the sheets when arranged in numerical sequence from left to right constituting a continuous whole.

Similar reference characters refer to like parts throughout the several views.

The rails 1 and 2 are shown divided into blocks A, B, C, D and E by means of insulations 3 in the usual manner and track installations are shown connected to the exit ends of these blocks and designated by the same letters as the blocks to which they are connected. Each track installation embodies two relays and their armatures are indicated by small letters which will be used in connection with the armatures of the relays embodied in the locomotive installations.

In the present system we have used a generator 4 of alternating current connected to line wires 5 and 6 which extend along the track and each track installation embodies a wire 7, primary winding 8 of the main transformer, wire 9, armature *c* of a high resistance polar-neutral relay 10, wire 12, armature *a* of relay 13 and wire 14 connecting to line wire 5. Each relay 10 is controlled by the current in the track of the block ahead and has three conditions of energization, viz, positive, negative and de-energized. When the condition is either positive or negative, it attracts its armatures *a*, *b* and *c* and closes the circuit to the primary winding 8, but when it is de-energized, which occurs when its block of track is occupied, the circuit to the primary winding 8 is opened and the adjacent track installation for the next block in the rear is inoperative.

The vacuum tubes 15 and 16 are the generators of the control currents and their filaments receive current from the portion 17 of the secondary winding of the main transformer, the current passing over wires 18 and 19, variable resistance 20 and wire 21 to the filament of tube 15 and back over wires 23 and 24 to the winding 17. Current also passes over wire 18, adjustable resistance 25 and wire 26 to the filament of tube 16 and back over wire 24.

The secondary winding of the main transformer for the plate current of tube 15 consists of the parts 17 and 27, while that for the tube 16 consists of the parts 17, 27 and 28. The plate circuit of the tube 15 during the positive portion of the cycle of the current in wires 5 and 6, is over wire 23, coils 17 and 27, wire 32, coil 31 and wire 30 to the plate while the circuit during the negative portion is over the wire 30, coil 31, wire 32, condenser 38, wires 18 and 19, resistance 20 and wire 21. This circuit carries a pulsating current of high-frequency and causes a pulsating charge in the grid circuit of this tube 15, consisting of the wire 41, inductance coil 42, wire 43 extending therefrom to the grid leak 44 and condenser 45, and wire 46.

The coil 42 being the secondary of a transformer of which the coil 31 is the primary, a pulsating charge is impressed upon the

grid circuit and negative potential is charged on and discharged from the grid of tube 15, the condenser 45 and grid leak 44 preventing positive potential in the grid. This charge and discharge is probably both the cause and effect of the pulsations in the plate circuit and coil 31. The rate of vibrations and the wave lengths of the currents are controlled by the adjustable condenser 47 which shunts the coil 31.

The plate current of tube 16 flows in one direction from coils 27 and 28, over wire 36, inductance coil 35 and wire 34, and in the opposite direction from the plate over wire 34, coil 35, wire 36, condenser 39, wires 18 and 19, and adjustable resistance 20 to the filament. The plate current, therefore, never flows in the opposite direction through the coils 27 and 28 of the main transformer. The adjustable condenser 37 tunes the plate circuit of tube 16 into resonance with the plate circuit of the other tube. The condensers 38 and 39 serve to protect the transformer windings 27 and 28 from the surging of the high frequency current.

The grid of tube 16 is controlled by the inductance coil 31 of tube 15 acting on the inductance coil 48 which connects to the wire 24 by the wire 49 and to the grid leak 50 and condenser 51 by the wire 52. The wire 53 connects the grid of tube 16 to its leak and condenser. As the charge in this grid pulsates in unison with the charge in the grid of and with the current in the plate circuit of tube 15, the plate current of tube 16 also pulsates in such unison.

The reason for using two tubes is as follows. The trackside circuit comprising the rails and the wires 58 and 59 is lengthened and shortened by the trains passing over the block to which the installation is connected. This change in length of circuit would normally change the wave lengths of the plate circuit through the reaction between the inductance coils 57 and 35 which are inductively connected. But the frequency of the pulsations of this plate circuit is controlled by the grid circuit which includes the coil 48 which circuit always pulsates in unison with the plate circuit of tube 15 which is unaffected by any change in the trackside circuit. The rate of vibrations and wave lengths are therefore controlled by the tube 15 and its circuits. This tube may be of very much less capacity than the tube 16.

The inductance coil 35 of the plate circuit of tube 16 reacts on the fixed output inductance 56 and variable inductance 57, the latter being used to tune the trackside circuit to the plate circuit of tube 16. This trackside circuit comprises two wires 58 and 59 connected to the track at various points by means of wires 61 and 62 so that the current propagated in the rails will be practically uniform throughout the block. The

capacity condensers 63 prevent the current from the track batteries passing to the track-side circuit wires 58 and 59 and the adjustable inductances 64 are useful in tuning the local trackside circuits. If desired, the wires 61 and 62 of all but one of the connections between 58, 59 and the rails may be omitted.

In the drawings, we assume that the track in advance of block D is unoccupied for three or more blocks, and the high resistance relay E¹⁰ is therefore energized, holding up its armatures. The control current of track battery E⁶⁶ (not shown) passes rearwardly along the rail E¹, wire 67, relay E¹⁰, wire 68 and rail 2 back to battery E⁶⁶. This so energizes relay E¹⁰ that its armatures d and e are swung clockwise (Fig. 1) and an additional condenser 69 is shunted across the plate circuit of tube 15 by this armature d bridging the wires 70 and 71 and an additional condenser 73 is shunted across the plate circuit of tube 16 by the armature e bridging the wires 74 and 75. This lengthens the waves in these plate circuits and results in long waves being propagated in the track rails. These two wave conditions will be referred to hereafter as the "longer" and "shorter" wave lengths.

The control current for block D is derived from the battery 66 (Fig. 1), and flows over wire 77, resistance 78, armature 10^a, wire 79, choke coil 80 and wire 81 to rail D¹ and to high resistance relay D¹⁰, thence back over rail D², wire 82, choke coil 83, low resistance relay 13, wire 84, armature 10^b, and wire 85 to the battery. As relay 10 has high resistance, low resistance relay 13 is not sufficiently energized to attract its armature until a train short circuits the rails and cuts out relay 10, when relay 13 gets sufficient current to attract its armature and closes the circuit to the main transformer.

The train control installation of any block, therefore, is inoperative unless said block is occupied, at which time the relay 10 at the entrance end of the block is de-energized, as shown in Fig. 2. Should a train enter block C under these conditions, it would pick up no current as the main transformer circuit at the exit end of this block would be open. As block D is occupied and the blocks in advance are unoccupied, relay 10 at the entrance end of block E is energized, as is also relay 13 at the exit end of block D. Relay 10 at the entrance end of block D is de-energized and negative current flows over rail 1 of block C. Relay 10 at its entrance end is therefore negatively energized and the armatures d and e are swung counter-clockwise so that current of the shorter wave lengths pass to the rails of block B over the wires 61 and 62. As block B is occupied, no current passes to the rails of block A over the wires 61 and 130

62. The conditions in block D are therefore "clear," in blocks C and A are therefore "danger" and in block B, "caution."

These track installations therefore propagate substantially uniform electro-magnetic waves in the rails throughout the lengths of the blocks, the wave lengths or their absence being automatically determined by the occupancy of the track ahead, and such propagation taking place only in occupied blocks, thus saving current and insuring maximum life of the tubes.

The locomotive installation embodies two collector coils, 100 and 101, which connect to the grids of the vacuum tubes 102 and 103 as follows. From the coil 100 over wire 104, condenser 105, grid leak 106, and wire 107 back to the coil, an adjustable condenser 112 being mounted between the wires 104 and 107 to tune this circuit to resonance with one of the radio-frequency currents in the track. The grid circuit from coil 101 is over wire 108, condenser 109, grid leak 110 and wire 111 back to the coil 101, the adjustable condenser 112 being used to tune this circuit to resonance with the other radio-frequency track current.

The current for the filaments of these tubes passes from the two-voltage generator 113 over wires 114, 115 and 107 to the filament of tube 102, over wire 116 to the filament of tube 103, and wire 111, adjustable resistance 117 and wires 118 and 119 back to the generator.

35 When either of the collector coils 100-101 picks up current, negative potential accumulates in the grid to which the coil is connected. This obstructs the normal action of the tube and few electrons pass to the plate from the filament. When neither tube receives radio-frequency current, high voltage current flows from the generator 113 over wires 119 and 118, resistance 117 and wire 111 to filament of tube 103 and wire 116 to filament of tube 102. Plate current flows from the plates of both tubes to the windings 120 and 121 of a polar neutral relay over the wires 122 and 123, and thence over the wires 124 and 125 to the generator.

40 As the two coils 120 and 121 neutralize each other, the neutral armatures *a* and *b* are not attracted and the current flows over wire 114 to red lamp R and over wire 124', armature *b* and wire 119 to show that there is no radio-frequency current in the rails.

45 Current picked up by coil 100 causes the winding 120 to be de-energized and winding 121 to swing armature *c* to complete the circuits shown in Fig. 3, from wire 114, over yellow lamp Y, wire 126, armature *c*, wire 127, and armature *b*, while current picked up by collector coil 101 causes coil 121 to be de-energized and the armature *c* to swing to the position shown in Fig. 1, the current

flowing from wire 114 over green lamp G, 65 wire 128 and armature *c*.

But if both coils 120 and 121 are energized by reason of no current in the rails, or if the installation becomes inoperative, the circuit over wire 127 is opened and to 70 the red lamp is closed. At the same time, the circuit to the electro-magnetic valve 130, consisting of wires 114 and 131, armature *a*, and wire 132 and the wires 118 and 119, is opened. This valve is well known and 75 embodies a magnet or solenoid by which it is kept closed so long as it is energized, but when de-energized, this valve releases the pressure in the train line pipe and causes the brakes to be applied. 80

When, therefore, either coil 100-101 picks up current, one of the coils 120-121 attracts its armatures and holds the circuit to the electro-pneumatic valve 130 closed, but if neither receives current, the brakes 85 are applied. The three signal lamps indicate the condition of the track ahead, and referring to the description of the track installations, "clear" conditions in the occupied block result in a green lamp, "caution" 90 conditions result in a yellow lamp, and "danger" conditions in a red lamp burning in the cab. "Danger" conditions in the occupied block always cause the brakes to be applied, but "clear" and "caution" conditions do not. 95

The details of construction, the arrangements of the circuits and the ratios of the wave lengths may all be changed by those skilled in the art without departing from 100 the spirit of our invention as set forth in the following claims.

We claim:

1. In a train control system, means for propagating electro-magnetic currents of 105 predetermined wave lengths in the track rails, additional means for propagating electro-magnetic currents of predetermined wave lengths to control the wave lengths of the currents propagated by said first mentioned means, and electrically operated means controlled by direct currents in the rails of the track in advance to predetermine the lengths of said waves. 110

2. In a train control system, means for propagating electro-magnetic currents of 115 predetermined wave lengths in the track rails, additional means for propagating electro-magnetic currents of predetermined wave lengths to control the wave lengths of the currents propagated by said first mentioned means, and an electrically operated relay energized by direct current in the rails 120 of the track in advance to predetermine the lengths of said waves. 125

3. In a train control system, a vacuum tube and circuits therefor for propagating electro-magnetic currents in the track rails,

- a second vacuum tube and circuits therefor connected to the grid of the first named tube to determine the wave lengths of the current passing to said rails, and means to vary the circuits of said tubes to change said wave lengths according to conditions of the track ahead.
4. In a train control system, a vacuum tube and circuits therefor for propagating 10 electro-magnetic currents in the track rails, a second vacuum tube and circuits therefor connected to the grid of the first named tube to determine the wave lengths of the current passing to said rails, and means to vary the circuits of said tubes to change said wave lengths according to conditions of the track ahead comprising an electrically operated relay energized by direct current in the rails of such track ahead.
5. In a train control system for railways whose tracks are divided into blocks, a vacuum tube and circuits therefor connected to the exit end of a block to propagate 20 electro-magnetic currents in the rails of said block, a second vacuum tube and circuits therefor connected to the grid of the first named tube to determine the wave lengths of the current passing to said rails, and means connected to the entrance ends of the 25 rails of the next block in advance to selectively vary the circuits of said tubes and thereby the wave length of the propagated current according to the conditions of the track ahead.
6. In a train control system for railways whose tracks are divided into blocks, a vacuum tube and circuits therefor connected to the exit end of a block to propagate 30 electro-magnetic currents in the rails of said block, a second vacuum tube and circuits therefor connected to the grid of the first named tube to determine the wave lengths of the current passing to said rails, and means connected to the entrance ends of the 35 rails of the next block in advance to selectively vary the circuits of said tubes and thereby the wave length of the propagated current according to the conditions of the track ahead and comprising an electrically operated relay at such entrance end of the next block ahead and a source of current connected to the exit end of such block ahead.
7. In a train control system, a vacuum tube 55 and a grid and a plate circuit therefor, said plate circuit embodying an inductance, an output inductance energized by the inductance in the plate circuit and conductors connected to said output inductance and extending parallel to the track rails, spaced connections between said conductors and said rails to insure substantially uniform current therein, and a second tube and circuits therefor, and an inductance coupling between the 60 plate circuit of the second tube and the grid 65 circuit of the first tube whereby the wave length of the current passing to the rails is controlled by the second named tube.
8. In a train control system, a vacuum tube and grid and plate circuits therefor, a track-side circuit, an inductance coupling between the plate circuit of said tube and said track-side circuit, a second vacuum tube and grid and plate circuits therefor, inductance couplings between the plate circuit of the second tube and the grid circuits of both tubes whereby the wave lengths of the current passing to the track rails are determined by the second tube, and a polar-neutral relay energized by direct current in the rails of the 70 track ahead to control the operation of said second tube.
9. In a train control system, means for propagating electro-magnetic currents of predetermined wave lengths in the rails of 80 a track, said means comprising a vacuum tube a second vacuum tube and circuits therefor for determining such wave lengths, a pair of wires along the track conveying power current, a transformer connected thereto to supply proper current to said tubes, a relay to close the circuit from the power wires to said transformer, and an energizing circuit to said relay adapted to be closed by a train on the rails to cause the relay to close the transformer circuit so that 85 electro-magnetic current is propagated in the rails of the track when occupied.
10. In a train control system, means for propagating electro-magnetic currents of predetermined wave lengths in the rails of a track, said means comprising a vacuum tube, a second vacuum tube and circuits therefor for determining such wave lengths, a pair of wires along the track conveying power 90 current, a transformer connected thereto to supply proper current to said tubes, a relay to close the circuit from the power wires to said transformer, an energizing circuit to 95 said relay adapted to be closed by a train on the rails to cause the relay to close the transformer circuit so that electro-magnetic current is propagated in the rails of the track when occupied.
11. In a train control system, means for propagating electro-magnetic currents of predetermined wave lengths in the track rails, additional means for propagating electro-magnetic currents of predetermined wave 100 lengths to control the wave lengths of the currents propagated by said first mentioned means, and electrically operated means con- 105
- 120
- 115
- 125

trolled by currents in the rails of the track in advance to predetermine the lengths of said waves.

12. In a train control system, means for propagating electro-magnetic currents of predetermined wave lengths in the track rails, additional means for propagating electro-magnetic currents of predetermined wave

lengths to control the wave lengths of the currents propagated by said first mentioned means, and an electrically operated relay energized by current in the rails of the track in advance to predetermine the length of said waves.
